UNITED STATES PATENT OFFICE.

EDWARD CRAIG, OF ST. JOSEPH, MICHIGAN, ASSIGNOR TO SARANAC AUTOMATIC MACHINE CORPORATION, OF BENTON HARBOR, MICHIGAN, A CORPORATION OF DELAWARE.

HOOP-MAKING MACHINE.

Application filed January 12, 1924. Serial No. 685,735.

My invention relates to machines for making hoops for baskets or other receptacles, or for any other suitable purpose.

Generally stated, the object of the invention is to provide a novel and comparatively simple machine which can be operated with certainty and with comparatively high speed to produce hoops made from strips having their ends fastened together; the machine having means to receive one end of a hoop strip and then bend the strip into hoop form, with the ends thereof overlapping, and having means for then inserting fastening devices, such as staples, to secure the overlapping end portions of the strip together to produce the desired hoop.

It is also an object to provide certain details and features of construction and combinations tending to increase the general efficiency and the desirability of a hook making machine of this particular character.

To the foregoing and other useful ends, the invention consists in the matters herein-after set forth and claimed, and shown in the accompanying drawings, in which—

Fig. 1 is a front elevation of a hoop making machine embodying the principles of the invention.

Fig. 2 is a perspective of one of the hoops made on said machine.

Fig. 3 is a side elevation of said machine.

Fig. 4 is a detail section on line 4—4 in Fig. 1, on a larger scale.

Fig. 5 is a vertical section on line 5—5 in Fig. 4.

Fig. 6 is a horizontal section, on a larger scale, on line 6—6 in Fig. 1.

Fig. 7 is a detail, sectional view of the clutch mechanism for controlling the operation of the machine.

Fig. 8 is an enlarged vertical section on line 8—8 in Fig. 3.

Fig. 9 is an enlarged vertical section on line 9—9 in Fig. 3.

Fig. 10 is an enlarged vertical section on line 10—10 in Fig. 3.

Fig. 11 is an enlarged vertical section on line 11—11 in Fig. 3.

As thus illustrated the invention comprises a base 1 having a suitable upright pedestal 2 upon the upper end of which the stationary head 3 of the stapling machine is mounted. A vertical rod 4 is adapted to

reciprocate up and down in the pedestal 2, and is provided at its upper end with a head 5 to which the staple driver 6 and staple former 7 are connected, to reciprocate up and down in the head 3, in the usual and well known manner. The wire for the staples is fed to the stapling mechanism through a tube 8, by means of feed rolls 9, the latter being operated by a ratchet pawl 10 connected at its upper end to the head 5, a spring 11 being applied to control said pawl, whereby the wire is given a forward feeding movement each time the head 5 moves upward. The stapling mechanism, however, can be of any suitable or approved character, and will not require further description.

For the operation of said stapling mechanism a shaft 12 is mounted in a bearing 13 on the base 1, and in a bearing 14 suitably formed in the pedestal 2, having a pulley 15 for the operation thereof. A crank plate 16 is provided on the end of the shaft 12, within the housing provided by the pedestal 2, and is connected by a link 17 with the lower end of the rod 4, whereby the latter is reciprocated up and down to operate the stapling mechanism.

The means for holding the work, in order to form a hoop like the one shown in Figure 2, comprising a rotary plate 18 upon the periphery of which the hoop strip is bent to form the hoop. This plate 18 is mounted loosely on the sleeve 19, which latter is mounted loosely on the stationary axle or arbor 20 secured by bolts 21 to the pedestal of the body of the frame. The sleeve 19 has a pinion 22 at its inner end, and this pinion is engaged by a gear wheel 23 on the end of the shaft 24, which latter is mounted in bearings 25 and 26 on the body of the machine. The outer end of the sleeve 19 is provided with a crank arm 27 to which is pivoted a link 28, and said plate 18 has a clamping jaw 29 pivoted thereon at 30, the outer end portion of this jaw being pivoted on the link 28, whereby actuation of the arm 27 by the sleeve 19 will cause movement of said jaw toward and away from the stationary jaw 31 formed on the edge of the plate. A guide 32 is provided on the end of the stapler head 3, to receive the hoop strip 33 shown in dotted lines in Figure 1, and this guide is preferably pivoted at 34 and pro-

vided with a spring 35 to keep it normally raised, but permit tilting movement of the guide when the hoop strip is inserted therein and fed into position to be clamped at its 5 end between the jaws 29 and 31 previously mentioned. Movement of the arm 27 in one direction, relatively to the plate 18, will open the clamping jaws, while movement in the other direction will cause the jaws to grip 10 the end of the hoop strip. The arm 27 has a shorter arm 36 which is movable between the two stops 37 and 38, these stops having set screws 39 and 40 to adjustably or variably limit the movement of the arm 36, there- 15 by to provide means for regulating the clamping action of the clamping jaws.

A stationary plate 41 is supported on the sleeve 19 and is provided with eccentrically mounted rolls 42 which bear against the hoop strip while the latter is being bent around the form, the eccentric mountings for these rolls being provided with arms 43 connected by springs 44 to said plate upon which the rolls are mounted. The springs 44 tend to 25 pull the arms 43 in a direction to partially move the rolls about the axes of their eccentric mountings, so that the rolls will bear harder against the hoop strip, and if the hoop strip is of some thickness, the rolls will 30 be pressed outward against the tension of the springs 44, in a manner that will be readily understood, whereby the rolls 42 bear yielding- 35 against the hoop strip while it is being bent around the form. As shown, the axis of each roll is between the spring and the axis 40 of the eccentric mounting.

For ejecting the hoop from the form a shifting plate 45 is provided, as shown, on the sleeve 46 of the plate 41, and this plate 45 is provided with pins 47 arranged on the line of a circle, and in line with the hoop on the form, whereby shifting of this plate 45 in an outward direction will cause the pins 47 to bear against the inner edge of the hoop 45 and thereby dislodge the finished hoop from the form. This plate 45 is provided with ears 48, and a yoke 49 is provided on the machine body at 50, this yoke being in the form of a bell crank, and having its other 50 end connected by a link 51 with the eccentric cam device 52, of any suitable character, on the shaft 12 previously mentioned. The cam device 52 is of such character that the plate 45 will be shifted outward, just after 55 the end portions of the hoop strip are stapled together, thereby to dislodge the finished hoop from the form.

The plate 18 is preferably controlled by a friction brake device 53, which bears against 60 its inner side, and which has rods 54 extending therefrom through the plate 45 and through the stationary plate 55 on the body of the machine, there being coil springs 56 interposed between the plate 45 and the plate 65 55, to bear against the shoulders on the rod

54, whereby the brake shoe 53 is yieldingly held against the inner surface of the plate 18, so that the latter will always be stopped in the desired position.

The shaft 24 is operated by a sprocket chain 57, which latter is mounted on sprockets on said shaft and on the shaft 12 previously mentioned, whereby the two shafts rotate in the same direction, but it will be seen that the sprocket on the shaft 12 is desirably smaller than the sprocket on the shaft 24 so that the upper shaft rotates more slowly than the lower shaft. The pulley 15 is controllably connected with the sprocket 58 on the shaft 12, and thereby controllably connected with the sprocket chain 57, through the medium of clutch mechanism 59 operated by a foot pedal 60 pivoted at 61 on the base of the machine, it being observed that this pedal has the end thereof connected by a link 62 with the clutch control 63, which latter also controls the friction band brake 64 which is provided to stop the motion promptly when the power transmission thus provided is opened; it being understood that the sprocket 58 is loose on the shaft 12 so that operation of this sprocket by closing the clutch does not rotate said shaft, but merely operates the sprocket chain 57 to turn the hoop form of the machine. 95 The link 62 is connected by a link 65 with the cam device 66 on the shaft 24, whereby the clutch device 59 is both manually and automatically controlled. When the foot pedal 60 is depressed, the clutch 59 is closed 100 and the sprocket chain 57 is operated to operate the shaft 24, thereby to rotate the plate 18 with the hoop strip thereon. Another clutch 67 is provided, of any suitable character, and a rod 68 connects this clutch 105 to the cam device 69 on the end of the shaft 24, in the manner shown. Therefore, at the proper time, the rotation of the shaft 24 controls the clutch 67 through the medium of the rod 68, thereby connecting the pulley 110 15 to the shaft 12, so that the latter will be rotated at the exact moment to operate the stapling mechanism, thereby to insert the two staples 70 through the overlapping portions of the hoop strip. The foot pedal 60 115 is then released, and the machine stopped then is ready to receive the end of another hoop strip, after the finished hoop has been ejected by the actuation of the bell crank 49, in the manner described, which occurs just after the driving of the two staples. 120 Thus the depression of the pedal 60 starts the machine, and the three operations of bending and stapling and ejecting the hoop follow in proper sequence, automatically, 125 and then the foot pedal is released and the machine is stopped. It will be understood, of course, that the clutch mechanism 67 is also provided with a friction band brake 71, similar to the one shown in Figure 10, there- 130

by to stop the motion promptly when the clutch is opened.

Thus a machine is provided for receiving the end of the hoop strip, and for then bending the strip into the shape of a hoop, the stapling of the overlapping end portions of the hoop then following automatically, and the finished hoop being ejected automatically from the machine. It will be seen that the hoop form with the hoop strip thereon rotates to the extent of a full or complete rotation, and that during this time the stapling mechanism is idle, but as soon as the end portions of the hoop strip are lapped, in the manner shown, the clutch 67 is then automatically closed to cause the operation of the stapler, thereby to drive the two staples, as shown in Figure 2 of the drawings. Of course, while the stapling mechanism is operating to drive the two staples, the hoop form and the hoop thereon must be stationary, in order to receive the two staples, it being observed that the stapling head is made double, having two staple formers and two staple drivers, as indicated in Figure 1, whereby the two staples are driven simultaneously when the shaft 12 is rotated for that purpose. The stopping of the hoop form and the hoop thereon is produced by the cam device 66, at the proper time, so that the rotation of the hoop form is arrested just long enough to enable the double stapler head to insert the two staples in the desired manner. It will be understood that the parts are so relatively arranged, and so proportioned, that the operations occur in their proper sequence in the manner described. When the two staples are driven, the operator releases the foot pedal 60, it being understood that about the same time the finished hoop is ejected from the machine. Thus, and by reason of the friction brakes 53, 64 and 71, previously described, the machine is stopped in the exact position of the parts thereof necessary to receive the next hoop strip. This means, for example, that the rotary hoop form will stop approximately in the position shown in Figure 1, so that the jaws 29 and 31 will always be stopped in position to receive the end of the next hoop strip. Each time the machine is started by the depression of the foot pedal 60, the jaws 29 and 31 will close to grip the end of the hoop strip, and thus the entire machine is controlled by the single foot pedal. The jaw 31 is preferably detachably secured in place by the screw 72, as shown more clearly in Figure 4, so that this jaw can be removed from the plate 18 when such is necessary or desirable. The hoop, while it is being bent is pressed against the periphery of the frame by the rolls 42, so that the hoop is bent tightly upon the rotary form, and because of the manner in which said rolls are mount-

ed, as previously explained, the hoops may vary somewhat in thickness without affecting the operation of the machine.

If desired, a section of pipe 73 can be screwed into the socket 74, which latter is attached to the plate 75 which is fastened to the outer end of the arbor 20 by the screw 76, thereby to hold the keyed arm 27 against outward displacement from the sleeve 19, said section of pipe 73 being of a length to catch the hoops as they fall from the machine. In this way, the hoops are collected in a bunch, and then removed from the section of pipe upon which they are thus collected.

Thus it will be seen that a single controller 60 is common to the hoop bending instrumentalities and the staple inserting means, or fastener inserting means, and is operated by a single actuation thereof to cause the strip to be pulled through the tilting guide 32 and thereafter convert it into a free annular hoop which is discharged from the machine automatically. In other words, the operator merely steps on the treadle or controller 60, after inserting a hoop strip through the guide and under the gripping device 29, and the result of this depression is a finished hoop which is automatically expelled from the machine. The automatic gripping of the hoop strip, of course, is brought about by the initial rotation of the shaft 20, which takes up the lost motion between the lugs 37 and 38, as previously explained, so that the mechanism by which the gripping device is automatically controlled is actuated by the initial rotation of the shaft to take up the lost motion, whereby the gripping of the end of the hoop strip occurs practically before the torque of the shaft is sufficient to positively rotate the rotary hoop forming means. A single operation of the fastener driving means, automatically brought about in the manner explained, as the result of the single actuation of the foot treadle, is sufficient to drive a plurality of staples to fasten the ends of the hoop strip together.

Of course, the sequence of operations necessary to form and staple the hoop, and to eject it from the machine, is not only controlled by the one foot treadle 60, or other suitable controller, but it is also true that the single actuation of this controller is followed by the stopping of the machine in exact condition to receive another hoop strip. Therefore, the means for automatically stopping the machine are also controlled by this foot pedal, or other controller, so that it is not only true that a single actuation of this treadle is sufficient to cause the making and the ejecting of the hoop, but is also sufficient to restore the machine to full condition to receive another hoop strip.

What I claim as my invention is:

1. In a power operated machine for making hoops, the combination of instrumentalities for receiving and bending a hoop strip into shape, with the end portions thereof in lapped relation, by one continuous and complete rotation of said instrumentalities for each hoop, means to cause said rotation, automatic mechanism for automatically inserting fastening means, timed to operate only upon the completion of each said complete rotation, thereby to secure the lapped portions of the hoop strip together by a single operation of said mechanism, a single controller common to said instrumentalities and mechanism, and means cooperating with said controller to cause by one actuation thereof the automatic operation of said instrumentalities and mechanism in sequence and the final automatic stopping of the machine in exact condition to receive another hoop strip.
2. A structure as specified in claim 1, said instrumentalities comprising a rotary form and means for bending the hoop strip thereon.
3. A structure as specified in claim 1, said instrumentalities comprising a rotary form having automatically opening and closing jaws to seize the end of the hoop strip, one of said jaws being pivoted and automatically controlled by the rotation of the form.
4. A structure as specified in claim 1, said instrumentalities comprising a rotary form, and means for bending the hoop strip thereon, in combination with an automatic ejector operated by the power that drives the machine for displacing the finished hoop from the form after the operation of said fastener inserting mechanism.
5. A structure as specified in claim 1, said fastener inserting mechanism comprising staplers for inserting a plurality of staples in the lapped portions of the hoop, in combination with means for automatically causing the operation of said mechanism upon the completion of the rotation of the hoop form, whereby said mechanism is prevented from operating during the rotation of said hoop form with the hoop strip thereon.
6. A structure as specified in claim 1, said instrumentalities comprising a rotary form, eccentrically mounted rolls for pressing the hoop strip upon the periphery of said form, springs controlling the eccentrically mounted rolls, so that each roll has movement about the axis of its eccentric to bear more or less upon the hoop, and means for gripping the end of the hoop strip to bend the latter around the form, automatically controlled by the rotation of the form.
7. A structure as specified in claim 1, in combination with a tilting guide in position to direct the end of the hoop strip into position between said mechanism and said bending instrumentalities, said controller being

operative by one actuation thereof to cause the pulling of the strip through said guide and the conversion thereof into a hoop.

8. A structure as specified in claim 1, said mechanism comprising staplers for inserting a plurality of staples at the same time, in combination with means for preventing movement of the hoop bending instrumentalities during the insertion of said staples, whereby the completely bent hoop is stationary while the staples are being inserted through the lapped end portions thereof.

9. A structure as specified in claim 1, in combination with automatic devices to automatically start the operation of said mechanism at the proper time, whereby said mechanism is prevented from operating until after the hoop strip is fully bent into position with its ends in lapped relation.

10. A structure as specified in claim 1, in combination with automatic means operated by the power that drives the machine to eject the finished hoop from said instrumentalities, upon the completion of the operation of said fastener inserting mechanism.

11. A structure as specified in claim 1, in combination with friction brake means for said instrumentalities, to control the operation set in motion by said controller.

12. In a hoop-making machine, the combination of a shaft and rotary instrumentalities thereon to bend the hoop strip into hoop form, having a device to seize the end of the hoop strip, there being some lost motion between said shaft and instrumentalities, and means whereby said device is automatically controlled by the rotation of said shaft, whereby the initial rotation of said shaft to take up the lost motion, after the hoop strip is fed into position, serves automatically to operate said device to seize the end of the hoop strip, whereby the said strip is then bent into hoop form.

13. A structure as specified in claim 12, in combination with automatic means for ejecting the finished hoop from the machine.

14. A structure as specified in claim 12, in combination with means to automatically stop the rotation of the hoop forming means when the hoop is fully bent or formed, whereby fastening means may then be inserted while the hoop is stationary to fasten the lapped ends thereof together.

15. A structure as specified in claim 12, in combination with automatic means for stopping the rotary motion of the hoop when fully bent or formed, and mechanism for then stapling the lapped end portions of the hoop together.

16. In a hoop machine, the combination of a rotary form, a shaft loosely supporting said form, an arm fixed on said shaft, stops fixed on the form at opposite sides of said arm, providing a lost motion connection be-

tween the shaft and the form, a jaw rigid with the form, a jaw pivoted on the form, and a connection between said arm and said pivoted jaw, said lost motion connection 5 thereby operative to automatically actuate said pivoted jaw toward and away from said other jaw, thereby to grip and release the end portion of the hoop strip.

17. In a hoop machine, the combination 10 of a controller for the machine, means controlled thereby to form the hoop, means controlled thereby to drive one or more staples

in the hoop, means controlled thereby to eject the finished hoop, and means controlled thereby to finally restore the machine to exact condition to receive another hoop strip, 15 all operative by a single actuation of said controller to cause the making of the hoop, the automatic ejection of the hoop from the machine, and the automatic return of the 20 machine to full condition to receive a fresh hoop strip.

EDWARD CRAIG.
